Application July 29, 1955, Serial No. 525,404

3 Claims. (Cl. 200—5)

(Granted under Title 35, U. S. Code (1952), sec. 266)

The invention described herein may be manufactured and used by or for the Government of the United States of America for governmental purposes without the payment of any royalties thereon or therefor.

This invention relates to an intervalometer and more particularly to an improvement in intervalometers of the drum contact selector switch type of the nature disclosed in application Serial No. 337,255, filed February 16, 1953, by Robert K. Bole and Maurice H. Baller.

The present invention has been designed primarily for regulating the firing order of an array of shipboard projectiles, commonly known as hedgehogs, such that the projectiles may be activated in any desired sequence and at non-uniform intervals of time between successive initiating pulses. To insure a simultaneous deposit of all the projectiles on a relatively large target area, the missiles, which must be launched to various ranges of the target area, are required to be fired at different time intervals. Sequence switches are normally employed for controlling the firing order of the projectiles to achieve a simultaneous blanket coverage of the target area. Known intervalometers adapted for use in the environment of hedgehog projectile firing have operated on the principle of uniform time intervals between activating pulses. This principle is inherently disadvantageous since a regular rhythm of vibration which may damage the missile launching equipment is created.

An object of the present invention is to provide an intervalometer for initiating the activation of a plurality of projectiles in any desired sequence.

Another object is the provision of an intervalometer for initiating the activation of a plurality of projectiles in any desired sequence and at non-uniform intervals of time between successive initiating pulses to prevent launching vibrational forces from becoming accumulative.

Another object is to provide an intervalometer designed to fire an array of projectiles on shipboard at non-uniform intervals in such order that they will arrive at the target area at the same time and in a pattern of distribution that will blanket a submerged target.

A further object is to provide a conductive drum assembly with a plurality of contactor points circumferentially and longitudinally spaced on the drum to afford a desired sequence of pulses at non-uniform intervals of time between the successive pulses.

Still another object is the provision of a sequence switch of the conductive rotative drum type having replaceable insulating rings slip mounted on the drum to carry electrical contacts.

A further object is to provide an intervalometer having stationary brush contacts which are cammed into electrical engagement with the rotating contacts in a manner which aids in keeping the contacts engaged while undergoing shock, and extends the life of the brush contacts.

Other objects and many of the attendant advantages of this invention will be readily appreciated as the same becomes better understood by reference to the follow-

2

ing detailed description when considered in connection with the accompanying drawings wherein:

Fig. 1 which shows a plan view partly broken away of a preferred embodiment of the present invention;

Fig. 2 illustrates a side elevation of the apparatus shown in Fig. 1;

Fig. 3 is an end view of the preferred embodiment shown in Fig. 2;

Fig. 4 shows a section of the device taken substantially along line 4—4 of Fig. 1 looking in the direction of the arrows;

Fig. 5 illustrates in detail a drum contact and its associated recessed ring seating; and

Fig. 6 is a fragmentary perspective view of the cam portion of the insulating ring.

Referring now to the drawings, wherein like reference characters designate like or corresponding parts throughout the several views, there is shown in Fig. 1, a shaft 10 which is intended to be motor driven at a constant speed, 20 and which may be hand driven on occasion, by means not shown, as, for example, when the necessity for contact checking arises. The shaft 10 carries a conductive drum 11 of suitable material such as metal on which is slip mounted a series of rings 12 of insulating material. Each 25 ring 12 is of stepped cross-sectional contour consisting of a high peripheral portion 13 and a low peripheral portion 14, the ultimate drum contour resulting from the assembly of the rings on the drum producing a succession of grooves 15. Each of the grooves is occupied by a 30 contact leaf spring 16 which is held by an insulator bar 17 in fixed relationship to the revolvable drum 11 normal to the axis of shaft 10. As best shown in Fig. 5, each of the rings 12 have a recess formed on one face 18 of the high peripheral portion 13, which recess extends into 35 the low peripheral portion 14. The composite recess accommodates a J-shaped contact 19, illustrated in Fig. 5, which is held in fixed position by a screw 21 which passes through a smooth hole in the ring 12 and is driven into a tapped hole 22 in the drum 11. The screw 21 thus serves to secure the contact to the ring, to secure the contact and ring to the drum, and to provide electrical continuity between the drum and the contact.

In securing the ring 12 to the drum 11 the screw 21 also functions to locate the ring 12 both angularly and longitudinally on the drum 11. A cam 23 on ring 12 is located approximately 180° diametrically opposite contact 19 on the ring face 24 opposite that face on which contact 19 is positioned. Each of the cams 23 of rings 12 are of the same size in circumferential extent and each 45 are in the same angular relationship with the respective recesses in face 18 of the rings. It can be readily appreciated that any program of activation of the contacts 19 may be established by the relative positioning of the contacts with each other on the conductive drum 11. In 50 other words, orientation of the contacts 19 on the drum 11 is made in such a manner that either uniform or non-uniform time intervals may exist between activation of the numerous contacts 19.

Leaf spring contact brushes 16, shown best in Figs. 60 2 and 3, are fixedly mounted on insulator bar 17 by a threaded member 25 which passes through a hole provided in the insulator bar 17. Shake-proof soldering lugs 28 are by means of the threaded coupling member 25 held in superjacent relationship with the tang of the 65 contact brush 16. Shims 29 are placed between the tang 26 of leaf spring contact brush 16 and the metal bushing 27 and held in position by the threaded coupling member 25 to provide a fine adjustment of the point of engagement of the spring 16 with the contact 19. By 70 removing or adding shims 29 from beneath the tang 25 of the brush 16 the point of engagement between the spring and the contact may be set either forward or back-

ward, thus setting the time for contact between brush 16 and contact 19 to a precise point and allowing exact non-uniform timing to be made between contacts.

The cam 23 of one ring 12 is adapted to depress the spring brush 16 of the ring 12 next to it. As the cam advances on the spring, the cam passes leaf portion 31 of spring brush 16 and the next adjacent ring surface without making engagement, but when the cam reaches the curved terminal 32 of the brush, which extends below the normal plane of the spring 16 and into the path of the cam 23, lateral deflection of the spring occurs with the result that a convolution 33 of spring 16 is forced into brushing engagement with the contact 19.

The mode of actuating the spring 16 against the contact 19 has the advantage of leaving the spring brush relaxed when the drum 11 is at rest and during the time the drum is revolving with the cam 23 disengaged from brush 16. Spring deflection is therefore reserved for the moment of making contact and thereby wear on the spring 16 and the ring 12 is reduced. Further, when spring brush 16 is contained between the cam 23 and the contact 19, it is positively held against the contact even under moderate conditions of shock.

The operation of the invention can be understood by visualizing an array of projectiles set up in horizontal rows for firing. The object is to set off the projectiles in such order that they will arrive at the target area at the same time and in a pattern of distribution that will blanket the submerged target vessel. It is easy to see that since the projectiles are set up in close order and that from there they must spread out over the near, far, side and intermediate reaches of an enormously enlarged target pattern, it becomes necessary to project the missiles to various ranges by projection at various angles of elevation or by other means. Projecting the missiles to various ranges from a point which is essentially fixed in spaced results in trajectories with various flight times, and in nonuniform increments of change between successive flight times.

Therefore, the contacts 19 will be staggered on the drums, some close together, others farther apart in the circumferential direction as shown in Fig. 1. The distribution of the contacts 19 is so arranged that firing will occur at non-uniform intervals, the character of the non-uniformity being tailored to fire the projectiles for the far, intermediate, and near trajectories at the proper time. The program of firing or activation of the contacts 19 can be arranged so as to fire the projectiles in accordance with any desired target pattern. A timing sequence for firing the projectiles at various ranges is predetermined, and holes 22 are tapped into drum 11 to correspond with this sequence. The insulating rings 12 are then mounted on the drum, and screws 19 fix the contacts 19 and rings 12 into position. Contact brushes 16 are then stationed by means of insulator bars 17 and shims 29 into assembly with drum 11, and electrical continuity is thereby completed from drum 11 through contacts 19 to brush contacts 16, and from the brush contacts 16 through coupling member 25 to lugs 28 to which are connected electrical leads.

Obviously many modifications and variations of the present invention are possible in the light of the above teachings. It is therefore to be understood that within the scope of the appended claims the invention may be practiced otherwise than as specifically described.

What is claimed is:

1. An intervalometer comprising a rotatable electrically conductive drum, a plurality of insulating rings

of stepped cross-sectional contour stacked on the drum in side-by-side relationship to form a series of annular grooves on the periphery of the drum, drum contacts carried by the rings on the face thereof which forms one side of the annular grooves and extending across the portion of said rings forming the bottom of the grooves, said rings each being provided with a passage communicating the drum with the drum contacts, cam surfaces located on said rings diametrically opposite the drum contacts and on the other face of said rings which forms the other side of the annular grooves, electrically conductive fastening means positioned on said rings connecting the drum contacts to the conductive drum via the passages provided through said rings at the portion forming the bottom of the grooves, and brush means fixedly positioned about the periphery of said drum and extending into the grooves thereon, said brush means being biased into engagement with the drum contacts by said cam surfaces.

2. An intervalometer comprising a rotatable electrically conductive drum, a plurality of insulating rings of stepped cross-sectional contour stacked on the drum in side-by-side relationship to form a series of annular grooves on the periphery of the drum, drum contacts carried by the rings on the face thereof which forms one side of the annular grooves and extending across the portion of said rings forming the bottom of the grooves, said rings each being provided with a passage communicating the drum with the drum contacts, cam surfaces located on said rings diametrically opposite the drum contacts and on the other face of said rings which forms the other side of the annular grooves, electrically conductive fastening means positioned on said rings connecting the drum contacts to the conductive drum via the passages provided through said rings at the portion forming the bottom of the grooves, and leaf spring contact brushes fixedly positioned about the periphery of the drum and extending into the insulating grooves on said drum, said brushes normally being engaged by the cam surfaces of the rings to contact the drum contacts.

3. An intervalometer comprising a rotatable electrically conductive drum, a plurality of insulating rings of stepped cross-sectional contour stacked on the drum in side-by-side relationship to form a series of annular grooves on the periphery of the drum, drum contacts carried by the rings on the face thereof which forms one side of the annular grooves and extending across the portion of said ring forming the bottom of the grooves, cam surfaces located on said rings diametrically opposite the drum contacts and on the other face of said rings which forms the other side of the annular grooves, electrically conductive fastening means positioned on said rings connecting the drum contacts to the conductive drum via passages provided through said rings at the portion forming the bottom of the grooves, insulator bars laterally and circumferentially spaced about said drum with their axes parallel to the axis of the drum, leaf spring contact brushes held by each of the insulator bars and extending into the insulating grooves on the drum, and means provided on said bars to adjust the extension of the brushes into the grooves, said brushes being engaged by the cam surfaces of the rings to contact the drum contacts.
